UNITED STATES PATENT OFFICE

ARTHUR BÜTTNER, OF HEIDELBERG, GERMANY, ASSIGNOR TO SCHNELLPRESSENFABRIK AKTIENGESELLSCHAFT HEIDELBERG, OF HEIDELBERG, GERMANY

CYLINDER PRINTING PRESS

Application filed June 22, 1929, Serial No. 372,998, and in Germany June 3, 1926.

This invention relates to cylinder printing presses and more especially to a delivery-device for such printing presses.

In cylinder printing presses the carrying 5 out of the printed sheets is effected in such a way that the sheet is delivered either above the inking mechanism or behind the inking mechanism in its running direction. If the printed sheets are delivered above the 10 inking mechanism or if the latter is arranged on the other side but still above the frame of the machine, the height of the delivery pile is very small, which is often very disadvantageous in the case 15 of an automatically working machine. If, however, the printed sheets are delivered behind the inking mechanism, then although a high delivery pile is possible, the machine is at the same time exceedingly long, and 20 the accessibility of the inking trough is seriously impaired.

It is the object of my invention to obviate these disadvantages. The invention consists essentially in the fact that the printed sheet 25 delivered by the impression cylinder passes on to a conveying device moving transversely to the previous direction of movement of the sheet, and is carried out of the printing press by means of this conveying device. 30 As a conveying device there may advantageously be employed a band-conveyer travelling out sideways to left or right. The movement of the conveying device is preferably effected in such a way that there are 35 always several sheets collected for lateral removal, so that for instance after every five impressions the sheets are conveyed to the delivery pile. By this method of delivering the sheets it is possible, in given jobs to 40 work off the feeding pile without interruption. Furthermore piling boards may be inserted during the working of the machine, so that the delivery pile is subdivided into small piles.

45 The invention is illustrated in one constructional form by way of example as applied to a cylinder printing press with oppositely moving impression cylinder and forme-bed in the accompanying drawings, in which

Figure 1 is a side elevation or longitudinal section through the printing press, and Figures 2 and 2a are a plan view.

From the feeding pile *a*, a sheet *b* is taken and delivered over a feeding table *c* in usual manner right against the laying-on marks *d*. Here the sheet is brought into the correct position by means of known side-registering marks. Meanwhile the impression cylinder *e*, journalled on the axle *e*² in a carriage *e*³, 55 has moved relatively to the feeding table *c*. The cylinder grippers *f* now seize the sheet. During the next revolution and motion of the cylinder *e* that now ensues, the impression is produced. Hereby, the impression cylinder *e* moves, together with the roller inking mechanism *g* arranged in the carriage *e*³, right into the position *e*¹ indicated by dotted lines in Figure 1, in a direction opposite to the direction of movement of the 60 forme bed *h*. In this position the front edge of the printed sheet is seized by delivery grippers *i*, which are reciprocated in a known manner by revolving chains *k* arranged on both sides of the machine frame. 65 The sheet *b* now comes first on to the band group *l* of a so-called Babcock slide bracket *l*¹ for delivery. This slide bracket *l*¹ is moved transversely to the previous direction 70 of movement of the sheet, the movement being such that for instance five printed sheets are always accumulated. The delivery of the sheets is thereby effected exceedingly smoothly even at the maximum speed of printing, for there remains for the return 75 journey of the lateral conveyer *l*¹, during which the sheets gradually lose their supports and slide on to the delivery pile *m*, the time of about four printing strokes. During this time the next five printed sheets 80 are already collected at the other end of the conveyer *l*¹.

The ink trough *n* and the rollers *o* of the revolving pregrinding inking mechanism are fully accessible and can be conveniently 85 operated. By the lateral delivery of the sheets according to the invention the press is only widened to a slight extent, since the drive *p* of the printing machine projects sideways itself. 90 100

What I claim is:—

1. In a cylinder printing press, the combination of a carriage mounted for reciprocating movement and having an impression cylinder and inking mechanism, a form bed mounted for reciprocating movement, said form bed and said carriage being movable simultaneously in opposite directions, a conveyor for delivering printed sheets, said conveyor being arranged and movable in a direction transverse to the path of movement of the carriage and form bed and means to grip printed sheets from the impression cylinder and to carry them above and across said conveyor and to directly deposit said printed sheets on said conveyor for delivery by the latter at a point at one side of the press.

2. In combination with printing mechanism, and means to facilitate the feeding of sheets thereto, means to grip the sheets and deliver the same from the printing mechanism and move the printed sheets in the direction of their movement while being fed to and printed by the printing mechanism and a conveyor arranged below said sheet gripping and delivery means to receive the printed sheets directly therefrom, said conveyor being arranged and movable in a direction transverse to the path of movement of the printing and gripping and delivery means, so that said conveyor delivers the printed sheets at one side of the press, in which the conveyor operates intermittently to accumulate a plurality of printed sheets thereon before moving said printed sheets for delivery at one side of the press.

In testimony whereof I have affixed my signature.
